ANCHORAGE FOR ARTIFICIAL TEETH

Rupert E. Hall, Houston, Tex.

Application July 26, 1948, Serial No. 40,757

7 Claims. (Cl. 22—2)

1

This invention relates to anchorage for artificial teeth.

Satisfactory anchorage of artificial teeth has heretofore been a dental problem which has not, to the present time, been satisfactorily solved.

This has been caused mainly for three reasons: dislodgement of the tooth from its anchorage because of breakage due to the frangibility of the material of which the tooth is made; or dislodgement of the tooth from its anchorage due to the frangibility of the retaining material; or dislodgement of both the tooth and the retaining material, intact, from the metal retaining frame, in the case of bridge and partial denture restorations, because of inadequate frame retention due to faulty design of the frame.

The difficult problem is to secure the tooth, the retaining material and the frame, all as a whole, against separation one from the other.

This requires a non-breakable tooth and a differently designed tooth and frame for better retention than has been, or now is, used.

An object of the present invention is to provide a tooth of the character described which will not break and thereby will prevent dislodgement of the tooth from its anchorage.

A further object of the invention is to produce a tooth which provides retention that allows for sufficient bulk of the retaining material so as to prevent the retaining material from breaking and which will thereby prevent dislodgement of the tooth from its anchorage.

A still further object of the invention is to produce a metal retaining frame of such design that it will provide retention adequate to secure the frame to the retaining material and thereby prevent dislodgement of the frame from its anchorage.

Other objects and advantages will be apparent from the following specification which is illustrated by the accompanying drawings, wherein:

Figure 1 is a mesial side view of a bicuspid tooth illustrating the invention.

Figure 2 is a similar view of the type of tooth shown in Figure 1, with the tooth material removed from openings into the retention cavity.

Figure 3 is a transverse, sectional view taken on the line 3—3 of Figure 4.

Figure 4 is a lingual view of the type of tooth shown in Figures 1 and 2.

Figure 5 is a cross-sectional view of the tooth as anchored to the denture and taken on the line 5—5 of Figure 6.

Figure 6 is a cross-sectional view of the assembly shown in Figure 5.

2

Figure 7 is a sectional view of another embodiment of the tooth.

Figure 8 is a sectional view substantially similar to that shown in Figure 7 but embodying a cross-pin, and

Figure 9 is a cross-sectional view taken on the line 9—9 of Figure 8.

Referring now more particularly to the drawings wherein like numerals of reference designate the same parts in each of the figures, the numeral 1 designates a type of tooth composed of suitable material such as methyl methacrylate resin reinforced with a hollow metal insert, as 2. This insert is provided for the purpose of reinforcing the tooth against breakage and forming the most spacious retention cavity 3 possible so as to receive sufficient bulk of the retaining material 4, of the denture, to prevent the retaining material from breaking and as best illustrated in Figure 6.

As shown in Figure 2 there is provided in the mesial side of the tooth 1, and the insert 2, an opening 5 into the retention cavity 3, said opening being restricted at its upper root end 6 to form a lock to secure the tooth to the retaining material.

As best shown in Figure 3 there is in the distal side of the tooth and the insert 2 an opening 7 which corresponds to, and is opposed to, the opening 5 which also forms a lock to additionally secure the tooth to the retaining material.

As clearly shown in Figures 3 and 4 there is another side opening 8 in the lingual side of the tooth 1. The openings 5, 7 and 8 are provided to receive the denture material to lock the tooth to the denture as shown in Figure 6.

In a tooth having the cavity 3 and the openings 5, 7 and 8 provision is made for adequate bulk of the retaining material 4 to give sufficient strength to the retaining material to prevent breakage and there will be sufficient retention to secure the tooth against dislodgement from its anchorage. This retaining material may be reinforced by a metal frame as 10 as shown in Figures 5 and 6.

One or more of the above mentioned side openings 5, 7 and 8 may be used at the discretion of the operator, all of them being closed with the tooth material, as shown in Figure 1, when molding the tooth subject to optional use of one or more of them as desired by removing said tooth material.

In the embodiment illustrated in Figure 7 the metal insert 2a is shown to extend to, and to form a part of, the occlusal surface of the tooth 1 and which also reinforces the cusps of the tooth.

In the event greater strength may be required in exceptionally short teeth, as indicated in Figure 8, a reinforcement insert, such as the cross-pin 11 may be provided to further increase the strength of the tooth.

The insert 2a is shown in Figure 8 to extend beyond the occlusal surface 12 of the tooth which allows for grinding in the occlusion of the tooth without grinding into and blunting the body of the tooth proper thereby impairing the masticating efficiency of the tooth.

While the illustrations do not show application of the invention to molar teeth and to anterior teeth, or to mechanically designed non-anatomical teeth, such as, for example, cuspless flat occlusal plane teeth, known as inverted cusp teeth, it is to be understood that it does apply to these teeth the same as it does to bicuspid teeth shown in the illustrations and described in the specification.

The illustrations shown and described depict teeth having adequate strength to secure them against breakage; retention sufficiently spacious to allow for bulk of the retaining material adequate to secure the retaining material against breakage; and design for the metal retaining frame providing adequate retention to prevent the frame from being dislodged from the retaining material, all of which secure the teeth, the retaining material and the frame, all as a whole, against separation one from the other.

The drawings and description are illustrative merely of what is now considered to be preferred embodiments of the invention by way of illustration only and not by way of limitation while the broad principle of the invention will be defined by the appended claims.

What I claim is:

1. An artificial denture comprising a denture plate formed of moldable material a tooth formed of moldable material and attached to said plate, a hollow tubular insert incorporated into the material of the tooth and which is open at the root end of the tooth, said insert having a side opening shaped to form a lock with the plate material and a cross-pin extending through the insert to reinforce the insert.

2. An artificial denture comprising a denture plate formed of moldable material, a tooth formed of moldable material and attached to said plate, a hollow axially disposed, tubular insert incorporated into the material of the tooth and extending beyond the occlusal surface of the tooth and which is open at the root end of the tooth, the root end of said insert having a plurality of marginal openings shaped to form locks with the plate material.

3. In an artificial denture the combination with a tooth having a transverse cavity to receive retaining material, of a denture plate formed

of moldable material, a retaining frame embedded in said plate and having an anchor which extends into said cavity and which reinforces the retaining material in the cavity.

5. An artificial denture comprising a denture plate formed of moldable material, a tooth formed of moldable material and attached to said plate, a hollow axially disposed, perforated insert as an integral part of the tooth, said insert being open at the root end of the tooth and at the lingual, mesial and distal sides of the tooth to form retention locks between the tooth material and the insert and between the plate material and tooth said insert extending from the root of the tooth beyond the occlusal surface thereof.

10 6. An artificial denture comprising a denture plate formed of moldable material, a tooth formed of moldable material and attached to said plate, a hollow axially disposed, perforated insert as an integral part of the tooth, said insert being open at the root end of the tooth and at the lingual, mesial and distal sides of the tooth to form retention locks between the tooth material and the insert and between the plate material and tooth, said insert extending to, and forming part of, the occlusal surface of the tooth.

15 7. An artificial denture comprising a denture plate formed of moldable material, a tooth formed of moldable material and attached to said plate, a hollow, perforated insert as an integral part of the tooth, said insert being open at the root end of the tooth and at the lingual, mesial and distal sides of the tooth to form retention locks between the tooth material and the insert and between the plate material and the tooth, said insert extending beyond said occlusal surface.

20 8. An artificial denture comprising a denture plate formed of moldable material, a tooth formed of moldable material and attached to said plate, an axially disposed tubular insert embedded in and surrounded by the material of the tooth and which is open at the root end of the tooth, said insert extending to and forming a part of the occlusal surface of the tooth.
